UNITED STATES PATENT OFFICE.

FREDERICK V. YOUNG, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,251,728.

Specification of Letters Patent.

Patented Jan. 1, 1918.

Application filed February 17, 1917. Serial No. 149,215.

To all whom it may concern:

Be it known that I, FREDERICK V. YOUNG, a citizen of the United States, residing at Newark, in the county of Essex and State 5 of New Jersey, have invented certain new and useful Improvements in Telephone-Exchange Systems, of which the following is a full, clear, concise, and exact description.

This invention relates to telephone exchange systems, and more particularly to 10 such systems which employ automatic ringing for signaling purposes and which are provided with trunk lines extending to private branch exchanges, chief operators' desks 15 and like positions.

The object of this invention is to prevent 20 the usual objectionable and disagreeable click in the answering operator's receiver when a call over the trunk to which a source 25 of ringing current is connected is being answered.

In accordance with a feature of this invention, when an operator answers the call 30 by actuating a listening key, a quick-operating and slow-releasing relay is operated to disable the answering operator's receiver before the tripping circuit for the ringing current is closed and to maintain the receiver disabled until after the ringing current has been cut off and talking current substituted therefor.

This invention is illustrated in the accompanying drawing in which all apparatus is 35 shown in its normal and unactuated condition.

There is shown in the drawing a telephone exchange system containing one embodiment of this system, and comprising a cord circuit A located at one section C of a 40 switchboard, and a trunk circuit B extending from this section C to a desk operator's position D at which there is a signaling device, a listening key and an operator's telephone set. It is believed that this invention 45 will be fully understood from a description of the operation of the system shown in the drawing and it will be so described.

The operator at section C, desiring to signal the desk operator D, inserts a plug 5

into a jack 6, whereupon lamp 7 will be 50 lighted and relay 8 operated. The operation of relay 8 causes the actuation of a ringing relay 9 over a circuit from battery through resistance 10, winding of ringing relay 9, normal contact of relay 11, contact 55 of tripping relay 12, and the closed contact of relay 8 to ground. The operation of relay 9 connects a source of ringing current 15 to the trunk circuit B, causing the operation of relay 16 over a circuit from the 60 source of ringing current 15 through the winding of tripping relay 12, lower alternate contact of ringing relay 9, ring contacts of the plug 5 and jack 6, contact 4 of listening key 18, condenser 17, lower winding 65 of relay 16, tip contacts of jack 6 and plug 5, and upper alternate contact of ringing relay 9 to ground. The operating winding of relay 16 is of high impedance so that the tripping relay 12 is not actuated when in 70 circuit with relay 16. Relay 16 upon being actuated is locked up over a circuit from battery through the two contacts of relay 16 in series, the upper winding thereof, and contact 3 of listening key 18 to ground. The 75 lamp 19 is lighted upon the actuation of relay 16 to furnish a signal to the desk operator, and remains lighted until the desk operator actuates the listening key 18. The ringing current also remains connected to 80 the trunk circuit until the actuation of the listening key by the desk operator.

The desk operator, upon observing the lighted condition of lamp 19, actuates the listening key, causing the following operations in the order named. 85

1. Opens contact 3 in the locking circuit of relay 16, causing the release thereof and the effacement of lamp 19. 90

2. Closure of contact 27, causing the operation of a quick-operating and slow-releasing relay 25 which short-circuits the answering operator's receiver 29 of the answering operator's telephone set. 95

3. The closure of contacts 40 and 41 connecting relay 26 across the tip and ring conductors of the trunk circuit. Tripping relay 12 and relay 26 thereupon operate. The

operation of tripping relay 12 permits the operation of relay 11, which in turn short-circuits and causes the release of ringing relay 9. Current from the battery in the 5 cord circuit A is thereupon substituted for ringing current over the trunk. Relay 26 operates at the same time tripping relay 12 operates, opening the circuit of relay 25.

4. The closure of contact 42 connecting 10 the answering operator's telephone set to the trunk circuit. Since relay 25 is slow in releasing, the operator's telephone set is connected with the trunk circuit before the short circuit is removed from the receiver 15 thereof.

When ringing relay 9 released, supervisory relay 30 is operated over a circuit from battery through winding 32 of repeating coil 33, winding of supervisory relay 30, 20 lower normal contact of ringing relay 9, ring contacts of the plug 5 and jack 6, contact 40 of listening key 18, winding of relay 26, contacts 41 and 42 of listening key 18, tip contacts of jack 6 and plug 5, upper normal 25 contact of ringing relay 9, and winding 37 of repeating coil 33 to ground. The operation of supervisory relay 30 places resistance 10 in parallel with the lamp 7, which is thereby effaced, indicating to the operator at 30 the section or position C that the desk operator D has answered. It will be noted that relay 26, after being operated by current from source 15, remains operated by current from battery in the cord circuit, thereby 35 maintaining the circuit of relay 25 open while the listening key is in its actuated position. Relay 26, therefore, serves as an impedance and holding coil.

From the above description, it will be 40 readily seen that a system embodying the present invention permits of the tripping of the ringing current and the connection of battery current to the trunk circuit while the answering operator's receiver is entirely 45 out of the circuit, thereby avoiding in the answering operator's receiver the disagreeable clicks usually attending the operation of tripping the ringing current. It will also be seen that by employing relay 26 as an impedance and holding coil, the calling subscriber connected to the other end of cord circuit C does not receive but the one click due to the initial actuation of the listening key, whereas, in former circuits, the calling 50 subscriber receives the click resulting from the initial operation of the listening key, and other clicks when the tripping relay was disconnected from the trunk and an impedance and holding coil substituted therefor. 55

60 What is claimed is:

1. A telephone exchange system comprising a trunk circuit extending from one telephone switchboard to a second board, means

at one of said boards for applying ringing 65 current over said trunk to the other board, an operator's telephone set at said other board, a switch thereat actuated by the operator for connecting the operator's telephone set to the trunk and for disconnecting the 70 ringing current from the trunk, means for disabling the receiver of the operator's telephone set during the period in which ringing current is being removed, and a relay connected with and operated over the trunk 75 while the switch is actuated to render and maintain the disabling means ineffective after ringing current has been removed.

2. A telephone exchange system comprising 80 a trunk circuit extending from one telephone switchboard to a second board, means at one of said boards for applying ringing current over said trunk to the other board, an operator's telephone set at said other board, a switch thereat actuated by the operator for connecting the operator's telephone set to the trunk and for disconnecting the 85 ringing current from the trunk, a relay for disabling the receiver of the operator's telephone set during the period in which ringing 90 current is being removed, an operating circuit for the relay completed by the actuation of the switch, and a relay bridged across and operated over the trunk while the switch is actuated to open the operating circuit of and 95 to maintain the first mentioned relay de-energized after ringing current has been removed.

3. A telephone exchange system comprising 100 a trunk circuit extending from one telephone switchboard to a second board, means at one of said boards for applying ringing current over said trunk to the other board, an operator's telephone set at said other board, a switch thereat actuated by the operator for connecting the operator's telephone set to the trunk and for disconnecting the 105 ringing current from the trunk, a slow releasing relay for disabling the receiver of the operator's telephone set during the period in which ringing current is being removed, an operating circuit therefor completed by the actuation of the switch, and a relay 110 bridged across the trunk by the actuation of the switch and energized while the switch remains actuated to open the operating circuit of and to maintain the slow releasing relay de-energized after ringing current has been removed. 115

4. A telephone exchange system comprising 120 a trunk circuit extending from one telephone switchboard to a second board, means at one of said boards for applying ringing current over said trunk to the other board, an operator's telephone set at said other board, a switch thereat actuated by the operator for connecting the operator's telephone set to the trunk and for disconnecting ring- 125

ing current from the trunk, means for disabling the receiver of the operator's telephone set during the period in which ringing current is being removed, and a relay 5 bridged across the trunk by the actuation of the switch and energized while the switch remains actuated to maintain the disabling

means ineffective after ringing current has been removed.

In witness whereof, I hereunto subscribe 10 my name this 16th day of February, A. D. 1917.

FREDERICK V. YOUNG.
